CLAIM

The ornamental design for a ground blind, as shown and described.

DESCRIPTION

FIG. 1 is a top front perspective view of a ground blind showing my new design;

FIG. 2 is a front elevational view thereof;

FIG. 3 is a right-side elevational view thereof;

FIG. 4 is a left-side elevational view thereof;

FIG. 5 is a rear elevational view thereof;

FIG. 6 is a top plan view thereof; and,

FIG. 7 is a bottom plan view thereof.

The broken lines showing small rectangles and selective elements on the bottom of the tent represent portions that form no part of the claimed design.
